SHAVING KIT

Filed Oct. 23, 1930

Fig. 1. A detailed cross-sectional view of a lamp assembly. The structure includes a base 32 with a flange 33, a lower housing 29, a central support 28, a middle housing 26, a top housing 25, a lamp head 23, a lamp socket 27, a glass shield 10, a reflector 11, a lamp base 13, a lamp bulb 14, a lamp cap 15, a lamp cord 16, a lamp socket 17, and a lamp base 18. The top housing 25 is secured with a screw 34 and a lock washer 35.

Fig. 2. A side view of the lamp assembly, showing the base 32, the lamp head 23, the glass shield 10, the lamp base 13, and the lamp cord 16.

UNITED STATES PATENT OFFICE

HARRY R. PRIEST, OF LOUDONVILLE, OHIO

SHAVING KIT

Application filed October 23, 1930, Serial No. 490,711.

This invention relates to all in one shaving kits and has for an object to provide a single unit containing all of the necessary apparatus and material for shaving and including a case, a shaving brush, a mirror, a shaving cream dispenser, a hard soap cap, a cap for water, a double suction cup for attaching the mirror to a convenient support, and a cap for housing the suction cup and cream dispenser, the entire assembly being small, compact and neat in appearance.

A further object of the invention is to provide a shaving kit in which the case for the shaving cup also forms a handle for the shaving brush, the end of the base being equipped with a plunger for forcing the shaving cream from the dispensing cap, so that the brush may be manipulated over the end of the dispenser to work up a lather, the plunger, the dispensing cap and the housing cap therefor forming part of the handle when the brush is in use and also permitting of the brush being stood on end without falling over.

A still further object is to provide a shaving cream dispensing cap, hereinafter called a refill cap, which is provided with a discardable base to permit easy storing in drug stores and the like and which may be conveniently screwed or slipped onto the end of the plunger and when in this position will economically dispense a desired quantity of shaving cream, the cap being inexpensively constructed so as to be used only until empty and then thrown away and replaced with a new full cap.

A still further object is to provide a hard soap cap, hereinafter called a refill cap, which is also constructed so as to be easily stored for sale in drug stores and the like and which may be screwed into the end of the shaving brush case and used only until empty, the cap being inexpensively constructed so as to be thrown away when empty and a new full cap substituted.

A further object is to provide a shaving kit in which the case for the shaving brush also forms a handle for the shaving brush, the end of the case being equipped with a plunger which is formed solid for forcing

the cream from the dispensing cap, the solid plunger forming part of the handle when the brush is in use and functioning to place the center of gravity low so that the brush may be stood on end without falling over.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a longitudinal sectional view through the shaving outfit showing the shaving brush housed in the case,

Fig. 2 is a side elevation with portions broken away and showing the brush in operative position,

Fig. 3 is a detail front elevation showing the mirror attached to a wall or the like by the double suction cup,

Fig. 4 is a cross sectional view through the cream refill cap, and

Fig. 5 is a detail sectional view showing the plunger formed solid.

Referring now to the drawings in which like characters of reference designate similar parts in the various views, 10 designates a case which may be formed of any suitable material and is provided with vents 11. The case is open at both ends and the top is provided with internal screw threads 12 to receive a plunger 13.

The plunger is closed at the top to provide a plunger head 14 and is open at the bottom. The plunger is reduced and externally threaded at both ends, as shown at 15 and 16, the lower threads 15 receiving the threads 12 of the case. The upper threaded end is considerably longer than the lower end to accommodate longitudinal movement of the cream dispensing refill cap 17.

The shaving cream refill cap 17 is open at the bottom and is internally threaded throughout its inner face, as shown at 18. The top of the cap is provided with a small

55

90

95

100

central discharge opening 19. The screw threads 16 at the top of the plunger engage the screw threads 18 of the refill cap. A single turn of the refill cap on the plunger serves to compress the cream and eject sufficient cream for a single shave, in contrast to the wasteful expenditure of cream resulting from the use of the usual cream tubes. By unscrewing the refill cap approximately 5 a quarter of a turn from the plunger, the surplus cream is sucked back into the supply 10 in the cap to further promote economy.

As shown in Fig. 4, a disk base 20 of slightly greater diameter than the refill cap 17 is 15 provided with a threaded portion 21 which is screwed into the cap after the cap has been charged with a supply of shaving cream. The base permits of easy stacking of the refill caps in storage in drug stores and the like and is discarded by the purchaser when 20 a fresh cap is to be applied to the plunger 13, as shown in Fig. 1, to replenish the shaving cream supply of the shaving kit. The refill cap is formed of inexpensive material 25 so that it may be thrown away when empty and replaced with a fresh filled cap at slight expense.

A shaving brush 22 is housed within the case 10, the brush preferably having the 30 bristles rubber set in a base 23. The base is provided with external screw threads 24 which are adapted to be engaged in the internal screw threads 25 in the bottom of the case when the brush is reversed to extend 35 from the case for use, as shown in Fig. 2. The base 23 forms a grip by means of which the brush may be manipulated upon the perforated top of the cream refill cap after a desired quantity of cream has been ejected, 40 to work the cream into the bristles.

A soap refill cap 26 is provided with an exteriorly threaded solid top 27 which is 45 screwed into the threaded bottom of the case when the shaving brush is nested, as shown in Fig. 1, and supports the brush. The soap refill cap is closed by a flanged base 28 which is provided with internal screw threads 29 to engage external screw threads 30 on the cap. The base may be unscrewed from the 50 soap refill cap to gain access to the soap. Furthermore, the base permits of easy stacking of the soap refill caps in storage in drug stores and the like, but in this case is not discarded by the purchaser. However, as 55 in the case of the cream refill cap, the soap refill cap may be discarded as an entirety when empty and replaced with a fresh filled cap, the cap being formed of inexpensive material for the purpose of cheap replacement.

60 By now referring to Fig. 1, it will be seen that a cap 31 of the push type is slipped onto the top of the plunger and houses the shaving cream refill cap. A similar cap 32 of the push type is slipped onto the soap refill cap and houses said cap. Since the outer faces

of the soap cap, the case, the plunger, and the cream refill cap are flush with each other, as shown in Fig. 1, the terminal caps 31 and 32 lend a balanced appearance to the kit as well as having further functions which will 70 now be described.

The cap 32 may be used as a measuring cap to contain a predetermined quantity of water sufficient for a single shave. The cap is provided in the end wall with a mirror 33. Also the opposite cap 31 is provided in the end wall with a mirror 34. If desired, either of the caps 31 or 32 may be used as a measuring cup for water while the other is used as a mirror, 80 and to attach the mirror to a convenient support, such as a window casing, wall or the like, I provide a suction cup, which will now be described. The suction cup preferably is formed of rubber and comprises a pair of 85 oppositely turned cups 35 having their centers 36 coinciding and integral. Either of the cups may be attached to the side of the cap 32, for instance, as shown best in Fig. 3, and the mating cup may be attached to a suitable support, it being simply necessary to press the cups against the support and against the cap whereupon they will adhere to the parts by suction.

The suction cup may be housed when not 90 in use in the cap 31, as best shown in Fig. 1, or may be housed in the cap 32, if desired.

By now referring to Fig. 5, it will be seen that a modified form of plunger is shown at 37. The plunger is solid throughout and in addition to having the usual function of a plunger, it also forms a counter-balancing weight which places the center of gravity of the assembled case and brush low when the parts are assembled, as shown in Fig. 2, so 100 that the brush may be stood on end on the cap 31, for instance, without danger of tipping over. Since the cream refill cap, terminal cap and case are identical in Fig. 5 with the parts 17, 31 and 10 above described, 105 like numerals have been used to designate the parts.

It will be pointed out that the above described shaving kit contains a supply of cream, a supply of soap, a shaving brush, two mirrors, a suction cup for attaching either of the mirrors to a support, and a measuring cup as well as a plunger for ejecting the cream, the latter in some cases being formed solid to provide a counter-balancing weight, 115 all of these parts being assembled in a single 120 unitary structure which in overall dimension approximates the size of the usual shaving brush and handle alone.

Having thus described the invention, I 125 claim:

1. A shaving kit comprising a case, a shaving brush housed therein adapted to be reversed to project from said case as a handle, a solid plunger carried by the case forming a counterweight when the case is used as a 130

handle for the brush to permit the handle being stood upright on end without tipping over, and a perforated shaving cream refill cap forming a part of said handle and manu-
5 ally movable on said plunger.

2. A shaving kit comprising a case, a brush housed in the case and adapted to be reversed and extended from the case whereby said case forms a handle for the brush,
10 a soap cap carried by said case and forming a support for the brush when the brush is nested in the case, a cap assembled with the case, a mirror carried by said cap, and a double suction cup comprising a pair of suction
15 cups with their centers coinciding, said suction cup being adapted to secure said mirror to a support.

3. A shaving kit comprising a case, a shaving brush housed therein and adapted to be reversed to extend from the case whereby said case forms a handle, a plunger carried by one end of said case, and a perforated refill shaving cream cap manually movable on the plunger.
20

25 4. A shaving kit comprising a case, a shaving brush housed therein and adapted to be reversed and extended from one end of the case, a plunger carried by the opposite end of the case, a shaving cream refill cap manu-
30 ally movable on the plunger, and a soap refill cap supporting the brush when the brush is housed in the case, said brush being interchangeable with the soap refill cap, said case said plunger and said cream refill cap form-
35 ing a handle for said brush when the brush is in use.

5. A shaving kit comprising a case, a shaving brush housed therein, a solid plunger screwed into one open end of said case, a soap
40 refill cap screwed into the opposite end of said case, said cap supporting said brush when nested in the case, a soap refill shaving cream cap threaded onto said plunger, terminal caps housing said soap refill cap and said
45 shaving cream refill cap, mirrors carried by said terminal caps, and a double suction cup housed in one of said terminal caps.

In testimony whereof I affix my signature.
HARRY R. PRIEST. [L. S.]
